CLAIM

The ornamental design for a cover for an electrical connector, as shown and described.

DESCRIPTION

FIG. 1 is a perspective view of a cover for an electrical connector showing our new design;

FIG. 2 is a front elevation view thereof, the rear being a mirror image of that shown;

FIG. 3 is a bottom plan view thereof;

FIG. 4 is a side elevation view thereof, the opposite side being a mirror image of that shown; and

FIG. 5 is a top plan view thereof.

FIG 1

FIG 2

FIG 5

FIG 3

FIG 4
